[57] ABSTRACT

An optical imaging system including a document supporting surface, a short conjugate imaging device and a cylindrically shaped light responsive member. The document to be reproduced is fixedly supported adjacent the light responsive member with the imaging device therebetween. The imaging device is moved in the direction opposite the direction of rotation of the light responsive member in an arcuate path concentric with the light responsive member and document supporting surface to thereby create a usable pattern on the surface of the light responsive member in conformity with the document being reproduced.

FIG. 2

OPTICAL IMAGING SYSTEM

This invention relates to a short conjugate length imaging system and in particular to an imaging system wherein an immovably supported document is imaged onto a moving light responsive surface by a short conjugate length imaging device moving therebetween.

In the process of xerography, as described in U.S. Pat. No. 2,297,691 to Chester F. Carlson, a xerographic surface comprising a layer of photoconductive insulating material affixed to a conductive backing is used to support electrostatic images. In the usual method of carrying out the process, the xerographic surface is electrostatically charged uniformly over its surface and then exposed to a light pattern of the image being reproduced to thereby discharge the charge in the areas where light strikes the layer. The undischarged areas of the layer thus form an electrostatic charge pattern in conformity with the configuration of the original light pattern.

The latent electrostatic image can be then developed by contacting it with a finely divided electrostatically attractive material such as powder. The powder is held in image areas by the electrostatic charges on the layer. Where the charge field is greatest, the greatest amount of material is deposited; where the charge field is least, little or no material is deposited. Thus a powder image is produced in conformity with the light image of copy being reproduced. The powder may then be subsequently transferred to a sheet of paper or other surface and affixed thereto to form a permanent print.

Most commercial xerographic reproducing machines in use today employ imaging systems requiring a large conjugate length between the original document and light responsive surface. In general, this distance must be about equal to twice the length of the diagonal of the document or portion thereof being imaged. With the trend toward more compact reproducing machines, it has been found desirable to employ imaging systems which could permit the reduction of the conjugate length and consequently the size of the imaging zone.

Imaging systems capable of projecting light images of an original document onto a light responsive member held a short distance away are described in pending applications Ser. Nos. 683,988 filed Nov. 17, 1967 in the name of Osmar A. Ullrich, Jr., et al. 683,837 filed Nov. 17, 1967 in the name of Robert W. Gundlach and 683,987 filed Nov. 17, 1967 in the name of Robert W. Gundlach et al. According to those disclosures, it is necessary to support the object being reproduced and the light responsive surface immovable with respect to each other during imaging. Imaging occurs in a flowing manner as the object and image surfaces are held fixed and the imaging device moves relative thereto. The imaged surface may then be developed and transferred to the final backing sheet.

Another short conjugate length optical imaging system is disclosed in Canadian Pat. No. 771,916 issued Nov. 21, 1967 in the name of Kaufer et al. In that disclosure, it is necessary to move both the light responsive surface and document being reproduced in opposite directions with respect to each other to effect correct imaging. The imaged sheet may then be developed to constitute the final copy.

Such prior art imaging systems are not universally suited for use in continuous and automatic xerographic reproducing machines. For example, expanded utility of the reproducing machine may be attained if the elements of the imaging station may be made to function in a continuous mode as the other xerographic processing stations.

This continuous mode cannot necessarily be attained if the light receiving surface must be stopped during the imaging step. Furthermore, the utility of a reproducing machine may be expanded if the original to be copied is held stationary during its imaging. When an imaging system permits the scanning of a fixed original, it then becomes easier to create copies of three-dimensional objects or the like. In such a fixed-original system, document handling is also minimized since the documents need never be grasped or forwarded by document handling mechanisms.

It is therefore an object of the instant invention to optically project an image of an object to be reproduced onto a light responsive member with a short distance therebetween.

It is a further object of the instant invention to flowingly image light rays of a fixedly supported object onto a moving light responsive member by projection along a short conjugate length.

5 It is a further object of the instant invention to dissipate an electrostatic charge on a rotating cylindrically shaped light responsive member in accordance with a light pattern projected from a document which is immovably supported.

10 It is a further object of the instant invention to create an electrostatic charge pattern on a light responsive surface of a rotating cylinder through a short conjugate length imaging system moving between the cylinder and a fixed document being reproduced.

These and other objects of the instant invention are attained in accordance with the present invention by an imaging system including a document supporting surface, a short conjugate length imaging device and a cylindrically shaped light responsive member. The document to be reproduced is fixedly supported adjacent the light responsive surface with the short conjugate length imaging device therebetween. The imaging device is moved in the direction opposite the direction of rotation of the light responsive surface in an arcuate path concentric with the light responsive member and document supporting surface to thereby create a usable pattern on the surface of the light responsive member in conformity with the document being reproduced.

Further objects together with additional features and advantages thereof will become apparent from the following description of one embodiment of the invention when read in conjunction with the accompanying drawings wherein:

FIG. 1 is a schematic representation of a continuous and automatic xerographic reproducing machine employing the imaging system of the instant invention and

35 FIG. 2 is a perspective view of the imaging system shown in FIG. 1.

Referring now to the drawings, there is shown an embodiment of the subject invention in a suitable environment such as an automatic xerographic reproducing machine. The automatic xerographic reproducing machine includes light responsive member 10 in the form of a xerographic plate or surface formed in the cylindrical shape of a drum. The plate has a photoconductive layer or light receiving surface on a conductive backing supported by drive shaft 12 journaled in the machine frame to rotate under the influence of a suitable power source, not shown, in the direction indicated by the arrow. The rotation will cause the plate surface to sequentially pass a series of xerographic processing stations. While the light responsive surface is shown as a xerographic surface it could be any light responsive surface, as for example, a photographic film.

For the purposes of the present disclosure, the several xerographic processing stations in the path of movement of the plate surface may be described functionally as follows:

55 A charging station A, at which a uniform electrostatic charge is deposited on the photoconductive plate;

An exposure station B, at which light or radiation pattern of copy to be reproduced is projected onto the plate surface to dissipate the charge in the exposed areas thereof to thereby 60 form a latent electrostatic image of the copy to be reproduced;

A developing station C at which xerographic developing material, including toner particles having an electrostatic charge opposite that of the latent electrostatic image, is cascaded over the plate surface whereby the toner particles 65 adhere to the latent electrostatic image to form a toner image in the configuration of the copy being reproduced;

A transfer station D at which the toner image is electrostatically transferred from the plate surface to a transfer material or a support surface; and

70 A drum cleaning and discharge station E at which the plate surface is brushed to remove residual toner particles remaining thereon after image transfer.

It is felt that the preceding description of the xerographic process is sufficient for an understanding of the instant invention.

In order to operate the imaging system of the instant invention it is first necessary to place the document or object to be reproduced on the transparent document supporting surface 14 in the object plane. The document supporting surface is in a curved orientation concentric with the portion of the cylindrical xerographic member 10 passed through the image plane in the imaging zone 16. The xerographic member need not be in the shape of a right circular cylinder. It could readily be an endless belt with a curved portion thereof passing through the imaging zone. Positioned between the document supporting surface 14 and the light responsive member 10 is the optical imaging device 18.

The imaging device is constructed in accordance with that disclosed in the aforementioned Gundlach et al. application. This device includes a plurality of transparent light refracting lens strips 20, 22 and 24 having lens portions 26 formed thereon. Lens strip 20 is positioned two focal lengths away from the object to be reproduced as well as the intermediate field lens 22. The lens portions 26 of this lens strip 20 are adapted to project light images from the document and to individually invert and revert the scanned segments of the image.

The lens strip 24, positioned two focal lengths away from the light responsive surface and intermediate field lens 22 will, in like turn invert and revert the images formed adjacent the field lens 22 to ultimately project upright wrong reading images of the scanned portions of the document onto the light responsive surface 10. This will thereby discharge the original charge on the drum into a latent electrostatic image corresponding to the document being reproduced. An aperture stop 28 and field stop 30 limit the intensity and amount of light projected from the document to the light receiving surface for ensuring an even imaging of the document across the drum. The aforementioned focal lengths and other parameters of the imaging elements are by way of example only since other lens strip configurations, including those creating reduced intermediate images, may be readily employed.

The various optical imaging elements including the lens strips and stops are secured in position with respect to each other by side support plate members 32 and light shielding plate members 34 which, like the lens strips, extend the length of the drum and document supporting surface thereby ensuring that the entire length of the document will be projected and imaged onto the xerographic surface. End support plates 36 support these side frames and imaging elements with respect to each other and define a light-shielded tunnel from an area adjacent the document supporting surface and xerographic drum. Tie rods 38 lend support to the assembly.

The end support plates 36 are mounted on shaft 12 for rotational movement in an arc concentric with the document supporting surface and drum shaped light responsive member. In this manner, the distance between the first lens strip 20 and that portion of the document supported on the document supporting surface being imaged can be maintained substantially constant during the oscillation of the imaging device. This arrangement also ensures that the distance between the lens strip 24 and the xerographic surface being imaged is, in like fashion, held at a substantially fixed distance during operation of the device. The ends of the side support plates 36, remote from the drum, also support lamps 40 which illuminate the object during imaging.

One of the end support plates 36 has a sprocket 42 secured thereto cooperable with chain 44 which is in turn coupled to 65 reversible motor MOT-1 to impart cyclical oscillating scanning motion to the imaging device.

The xerographic reproducing machine is started by activating the various processing stations including the imaging station. The drum shaped light responsive member 10 is then 70 rotated on the power imparting shaft 12 by its suitable power source to rotate a charged portion of the drum in the direction of the arrow to sequentially bring portions of the drum surface beneath the charging station to provide the uniform charge on the drum. When the leading edge of the charged portion of the

surface approaches the exit end 46 of the imaging zone 16, power source MOT-1 will be energized to start the imaging device to move in a direction opposite from the direction of rotation of the drum to thereby sequentially image the original document onto the drum in a flowingly fashion. After the imaging device 18 has traversed to the drum input end 48 of the imaging zone its motion will be reversed by the action of its motor to its start-of-scan position to begin a second imaging of a subsequent section of the xerographic surface 10. The return, or fly back, speed of the imaging device may be equal to the speed of the light responsive member to thereby facilitate the next start-of-scan on a segment of the light responsive member contiguous with that previously imaged. The machine could readily be programmed to stop after this or a predetermined number of cycles of the imaging device and consequently stop the creation of electrostatic images on the drum after a predetermined number of imaging cycles.

The imaged portion of the drum is then developed, transferred to a backing material such as a web 50 or a cut sheet synchronously contacting the image for fusing to create the final copy. The drum is then passed through the cleaning station prior to subsequent charging and imaging in a continuous and automatic cycle of operation.

The general speed of scan relationship for the instant embodiment may be expressed as $\alpha\beta = (r_2 - r_1)/r_1$ wherein α is the rotational speed of the light responsive member, β is the rotational speed of the imaging device and r_1 and r_2 are the distances from the center of curvature of the light responsive surface to the light responsive surface and to the object plane, respectively.

In one specific example for operating the imaging system of the instant invention, a 6-inch diameter drum was employed with the document supporting surface located to place the image in an arc 10 inches from the center of rotation of the xerographic drum. A lens strip was then positioned therebetween with the lens strips equally positioned with respect to each other as well as the document to be reproduced and the surface of the xerographic drum.

The drum was then rotated at 6.28 inches per second at its surface in a clockwise direction as shown in FIG. 1 while the imaging device was rotated at a linear speed of 8.97 inches per second at its extreme or 10-inch radius. The lens strip imaging device effectively traveled 2.69 inches per second at the 3-inch drum radius during the same 1 second in which the drum rotated 6.28 inches. In all, the drum had effectively traveled 8.97 inches with respect to the document during the same time that the lens strip traversed the entire length of the document.

While the instant invention has been described as carried out in a specific embodiment hereof, it is not intended to be limited thereby but it is intended to be protected broadly within the scope of the appended claims.

What is claimed is:

1. For use in the imaging station of a reproducing machine wherein a fixedly supported document is sequentially scanned by an optical system to produce a useable image pattern on a light responsive surface moving through the imaging station the combination including, a document supporting surface having an arcuate cross-sectional configuration adapted to have a document to be reproduced fixedly positioned thereon, a light responsive member positioned adjacent said document supporting surface to define an imaging zone therebetween, said light responsive member having a curved cross-sectional configuration in the imaging zone concentric with the document supporting surface, an imaging device positioned in the imaging zone, said imaging device including a plurality of transparent strips having lens surfaces formed thereon, said lens strip closest to said document supporting surface adapted to invert and revert light rays moving toward said light responsive member, said lens strip closest said light responsive surface being adapted to invert and revert

light rays past through said first lens strip and thereby project an upright wrong reading image toward said light responsive member,
means to move said light responsive member in a first direction through said imaging zone in a path concentric with the document supporting surface while said lens strips are projecting light images theretowards,
and means to move said imaging device in a direction op-

posite the direction of movement of said light responsive member in a path of movement concentric with said document supporting surface to thereby create a flowing representation of the imaged document on said light responsive surface, the speed of said imaging device and said light responsive member being correlated to maintain a 1:1 reproduction of the original document.
